OIL BURNER AIR CONTROL

Charles G. Sigwald, Minneapolis, Minn.

Application March 15, 1937, Serial No. 130,825

5 Claims. (Cl. 230—114)

This invention relates to an oil burner and particularly to an air control means for an oil burner.

The modern oil burner of the gun type as generally constructed comprises a somewhat elongated casing having an opening at its rear end. There is a fan in said casing and a motor for driving said fan. Air is drawn in through said opening, which air is blown out at the front of said burner mixed with atomized oil. Such oil burners are usually controlled by a thermostat and the operation thereof is stopped at intervals. When the burner has been operating the furnace becomes quite hot and when the burner is shut off the heat in the furnace and chimney causes air to pass therethrough, which air comes in through the rear of the burner casing. This passage of air begins as soon as the burner is shut off and as said air is of low temperature it has a decided cooling effect on the furnace and chimney. This cooling action lowers the efficiency of the system as the cool air is merely heated to pass up the chimney.

It is an object of this invention to provide means for closing the opening through the oil burner when the same is not in operation.

It is a further object to provide a simple, novel and efficient structure for controlling the flow of air through the oil burner.

It is still another object of the invention to provide a simple and efficient means for closing the rear end of the oil burner casing and regulating the flow of air therethrough.

These and other objects and advantages of the invention will be fully set forth in the following description made in connection with the accompanying drawing in which like reference characters refer to similar parts throughout the several views and in which:—

Fig. 1 is a central vertical section through the rear portion of the oil burner casing showing the fan and motor unit therein in side elevation;

Fig. 2 is a view in rear elevation of a cover for the burner casing;

Fig. 3 is a vertical section taken on line 3—3 of Fig. 1 as indicated by the arrows; and

Fig. 4 is a horizontal section taken on line 4—4 of Fig. 3 as indicated by the arrows.

Referring to the drawing, an oil burner is shown comprising a casing 10 of generally cylindrical form having a curved end 10a with a circular opening 10b in its rear end. Said casing 10 is cut away at its upper portions along the vertical line 10c and horizontal line 10d and the opening thus formed is closed by a cover

member 11 having a flange portion 11a overlying casing 10. A motor 12 is mounted in casing 10, a bracket or casting 13 being shown to which is also secured an oil pump 14. The armature shaft 12a of motor 12 is connected to a fan 15 which is driven by motor 12.

A cover member 16 is provided having a curved cylindrical flange 16a adapted to abut and fit against the rear end of casing 10 at the outer side of opening 10b. Member 16 is held in place against casing 10 by a plurality of lugs 17 having curved ends engaging the inner side of portion 10a and being secured to cover 16 by the headed screws 18 passing therethrough and being threaded into member 16. Member 16 has a cylindrical portion 16b, both ends of which are open and the inner end of which is disposed closely adjacent fan 15. The diameter of the opening through portion 16b is substantially the same as the air intake opening of fan 15. Portion 16b has a rib 16c at its inner side extending circumferentially therearound from its top and at either side thereof to a plane somewhat above the central horizontal plane passing therethrough. Said portion also has a similar rib 16d at its inner side passing therearound from the bottom upwardly to a horizontal plane a short distance below the plane in which the ends of rib 16c are disposed. A plate or disk member 19 is disposed in portion 16b, the same extending along and engaging the inner side of rib 16d and the outer side of rib 16c. It will be seen that plate 19 thus closes the opening through portion 16b.

Plate 19 has small ears or lugs 19a struck up at each side thereof somewhat above the center of the same and a small rod or wire 20 extends through apertures in said lugs and has its ends fixed in the sides of portion 16b. Member 20 is curved upwardly at its central portion as shown in Fig. 3 and is secured firmly to the disk or plate 19 by a headed and nutted bolt 21, the head of which is disposed inwardly and has between the same and member 20 a plurality of washers 22, the outermost washer engaging member 20. The washers 22 act to form a weight which acts to assist plate 19 in swinging to closed position as shown in full lines in Fig. 1 and also acts as a counterweight when the plate is swung. Member 16 has a circular opening 16e in its rear side and a plate 23 is secured to member 16 by a plurality of headed screws 24, plate 23 being somewhat larger in diameter than opening 16e. Plate 23 has a plurality of vertical openings or slots 23a therethrough including a central slot or opening 23b. Slot 23b acts as a guideway for a member

25 having a portion movable therein and projecting to the outer side of plate 23. Member 25 is somewhat curved and tapered at its inner side and the same extends inwardly to engage 5 the outer side of plate 19 when the latter is swung to open position. Plate 23 has a pair of vertically spaced lugs 23c, through which passes a headed screw 26, the same having a slotted head and having its shank threaded into the 10 projecting portion of member 25. A jamb or locking nut 27 is shown on screw 26 adapted to engage the underside of lug 23c.

In operation, when the burner is operating fan 15 will be rapidly rotated and will draw air 15 through the portion 16b and swing member 19 inwardly as indicated in dotted lines in Fig. 1. With member 19 so swung air can pass thereabout and will be supplied to the burner. The swinging movement of member 19 is limited by 20 the engagement thereof with member 25. Member 25 can be moved upwardly and downwardly by screw 26 so that the extreme open position of member can be variably determined. When the burner is not operating member 19 swings 25 to vertical or closed position and no air can pass through the burner at this time. It will be seen that plate 19 swings against ribs 16d and 16c which thus act as stop members. The members 22 as stated act as a weight tending to return 30 member 19 to closed position. As plate 19 swings open said weight swings partly across the center of member 20 or the axis of lugs 19a so that it acts as a counterweight tending to balance said plate. When the plate is near closed position 35 said weight acts almost entirely to move said plate to closed position. Cover member 16 can be quickly removed as can also plate 23.

From the above description it is seen that applicant has provided a simple and efficient 40 structure for an oil burner whereby when said burner is stopped in operation the draft through the burner will automatically be shut off. The heat in the furnace and flues will thus be conserved. The structure is quite simple and the 45 parts thereof are quite accessible. The device has been amply demonstrated in actual practice and found to be very successful and efficient.

It will, of course, be understood that various 50 changes may be made in the form, details, arrangement and proportions of the parts, without departing from the scope of applicant's invention, which generally stated, consists in a device capable of carrying out the objects above set forth in the parts and combinations of parts 55 closed and defined in the appended claims.

What is claimed is:—

1. An oil burner structure comprising a casing having an opening at its rear end, a cover member for said casing having an inwardly extending 60 open-ended cylindrical portion, a fan in said casing, means for driving said fan to draw air through said cylindrical portion, a disk member swingingly mounted in said cylindrical portion for closing the opening therethrough, said member being adapted to be swung open by operation 65 of said fan, said cover member having a vertically extending opening therethrough, a member adapted to have its inner end engage said disk member to limit opening movement of said disk 70 member and a screw mounted in the outer side of said cover and engaging said last mentioned member to move the same to different positions to variably limit the opening movement of said disk member.
2. An oil burner structure comprising a casing

having an opening at its rear end, a cover member for said casing extending about and over said opening, means engaging said member and the inner side of said casing wall to hold said member in place, said member having an inwardly extending open ended cylindrical portion projecting through said opening, a fan in said casing substantially coaxial with said portion, said fan being disposed closely adjacent the inner end of said portion and the opening through said portion being of substantially the same diameter as the intake opening of said fan, means for operating said fan to draw air through said opening, a substantially circular plate disposed in said cylindrical portion extending transversely there- 15 of and adapted to close the opening therethrough, means for swingably mounting said plate about an axis extending transversely thereof at one side of the center thereof, means secured to said plate for causing the same to move to closed position 20 by gravity when said fan is not operating, said plate being swung to open position when said fan is operating, and means carried by said cover at the outer side thereof for variably determining the open movement of said plate. 25

3. An oil burner structure comprising a casing having an opening at its rear end, a cover member extending about said opening and engaging said end, said cover member having a cylindrical portion with an opening extending therethrough, 30 said portion extending through said first mentioned opening, a fan within said casing disposed closely adjacent the inner end of said cylindrical portion, means for operating said fan to draw air through said cylindrical portion, a substantially 35 circular plate disposed in and extending transversely of said cylindrical portion, a pivot member secured to said plate and extending transversely thereof at one side of the center thereof and journaled in the sides of said cylindrical portion, means on said plate causing the same to swing to closed position by gravity, said cover having a slot therein, a member extending through said slot adapted to engage said plate to limit the swinging movement thereof and a 40 screw journaled in said cover and engaging said 45 last mentioned member to move the same to different positions for variably determining the opening movement of said plate.

4. An oil burner structure comprising a substantially cylindrical casing having an opening at 50 its rear end, a cover member engaging the outer side of said casing about said opening, means secured to said member and engaging said casing for holding said cover member in place, said member having a substantially cylindrical portion aligned with said opening, a fan in said casing substantially coaxial with said portion and disposed at the inner end thereof, means for operating said fan to draw air through said opening and portion, and a substantially circular plate disposed in said cylindrical portion extending transversely thereof and adapted to close the opening therethrough, means for swingably mounting said plate about a horizontal axis extending transversely thereof and means secured 60 to said plate for causing the same to move to closed position by gravity when said fan is not operating. 65

5. An oil burner structure comprising a casing having an opening at its rear end, a cover member having an opening at its rear end, a cover member for said opening having a cylindrical portion projecting through said opening, a fan within said casing adjacent the inner end of said 70 75

portion for drawing air through said portion, a substantially circular plate disposed in said cylindrical portion extending transversely thereof and adapted to close the opening therethrough, a small rod extending transversely across said plate above the center thereof, means on said plate for holding said rod in position, the ends of said rod

being journalled in opposite sides of said portion, said plate being swingably mounted about the axis of said end portions of said rod and means on said plate for causing the same to move to vertical closing position by gravity.
